UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR AND DOOR-OPERATING MECHANISM THEREFOR.

1,383,288.

Specification of Letters Patent.

Patented July 5, 1921.

Application filed August 27, 1920. Serial No. 406,235.

To all whom it may concern:

Be it known that I, ARGYLE CAMPBELL, a citizen of United States, residing at Chicago, in the county of Cook and State of Illinois, have invented a certain new and useful Improvement in Dump-Cars and Door-Operating Mechanism Therefor, of which the following is a full, clear, concise, and exact description, reference being had to the accompanying drawings, forming a part of this specification.

This invention relates to improvements in dump cars and door operating mechanism therefor.

One object of the invention is to provide a simple and efficient door operating mechanism for dump cars and more particularly for dump cars of the side dumping type used for coal, coke, et cetera, and where in the operator is required to position himself at the end of the car while unloading or closing the doors.

Another object of the invention is to provide a dump car and door operating mechanism therefor so arranged that the door operating mechanism may be conveniently and safely operated at the end of the car.

Other object of the invention will more clearly appear from the description and claims hereinafter following.

In the drawing forming a part of this specification, Figure 1 is an end elevational view of a dump car illustrating my improvements in connection therewith. Fig. 2 is a longitudinal central vertical section of the dump car shown in Fig. 1 and corresponding substantially to the line 2-2 of the latter. Fig. 3 is a vertical sectional view corresponding substantially to the line 3-3 of Fig. 2. And Fig. 4 is a detail view corresponding to the section line 4-4 of Fig. 2.

In said drawings, the car is designated generally by the reference letter A, the same being of that type having vertical side walls 10-10, vertical end walls 11-11, sloping end hopper bottom walls 12-12 and a central longitudinally extending ridge 13, dividing the car into side dumping hoppers, as clearly appears from Fig. 1. The car is provided along the sides thereof with a plurality of side dumping hopper doors 14-14, preferably four on a side, the same being hinged along their top edges in any suitable manner to the side sills or side

walls of the car. The draft sills of the car are indicated at 15 in Fig. 2, the bolster at 16 and the end sill at 17 with a narrow platform provided at 18 above the end sill. The end walls 11 of the car are suitably braced by angle posts 19-19. The ends of the individual hoppers are defined by transverse vertical hopper sheets 20-20, as indicated in Fig. 2, there being spaces between the hoppers as indicated at 21, to accommodate the elements of the door mechanism, hereinafter described.

The doors are all preferably operated simultaneously. Along each side of the car under the downwardly and outwardly sloping hopper sheets, is extended a shaft 22 mounted in suitable bearing brackets supported by the cross members of the car underframe and hoppers. Said shaft 22 is provided at intervals therealong with rigid arms 23 to which are pivoted bent links 24, the opposite ends of the latter being in turn pivoted as indicated at 25 to suitable brackets on the doors 14. As will be understood by those skilled in the art, the links 24 are connected to the doors at the ends of the latter or to connectors between the doors so that the doors may all be operated simultaneously. As clearly appears from Fig. 1, the points of pivotal connections at the ends of the links 24 are so disposed that a line joining the same will pass either through or slightly below the axis of the shafts 22 when the doors are in closed position. With this arrangement, the mechanism is made substantially self-locking and the shafts 22 relieved of torsional strain while carrying the load.

The shafts 22 are simultaneously operated by a plurality of chains or other equivalent flexible connections 26-26 which pass over sheave wheels 27 and 28 on the shafts 22 and shaft 29, respectively. As indicated conventionally in Fig. 1, one of the chains 26 will be crossed so that, as the shaft 29 is rotated in one direction, the two shafts 22 will be rotated in opposite directions due to the left and right hand mounting of the doors.

The shaft 29 is located just beneath the apex of the ridge 13, that is, it extends centrally horizontally and longitudinally of the car and for a distance slightly more than one-half of the length of the car. The center of the car is between the two sets of sheave wheels 28-28 and it will be seen that

the shaft 29 terminates slightly to the left thereof, as viewed in Fig. 2. Said shaft 29 is mounted in suitable bearings carried by the cross members of the car underframe, 5 the righthand end of the shaft, as viewed in Fig. 2, being extended through bolster extension plates 30—30 to a point approximately over the axle of the outer set of wheels. At said end, the shaft 29 is mounted 10 in suitable bearings provided by an up-standing casing or housing 31 mounted on the draft sills 15—15, as shown in Fig. 3. The housing 31 preferably consists of two counterpart sections adapted to be bolted 15 or otherwise rigidly secured together as indicated at 33—33. Inside of the housing 31, the shaft 29 has secured thereto a gear wheel 34, the latter meshing with a smaller gear or pinion 35, also contained within the 20 housing 31 and carried by a stud or short operating shaft 36. Movement of the shaft 29 to the left is prevented by a stop plate 37 and movement to the right is prevented by another stop plate 38.

25 The stud or operating shaft 36 is extended outwardly beyond the vertical plane defined by the vertical end 11 of the hopper. A suitable bearing is provided for said shaft 36 as indicated at 39, said bearing being carried 30 by a plate 40 riveted to two uprights 41—41. Outside of the plate 40, the shaft 36 carries a ratchet wheel 42 with which is adapted to coöperate a pivoted locking dog 43. A locking cam 44 of well known form is arranged to coöperate with the dog 43 to hold the latter in locked position.

Outside of or beyond the ratchet wheel 42, the shaft 36 carries a ratchet wheel 45 which is straddled by the forked ends 46 of 40 an operating handle 47. A reversible or double-acting pivoted gravity-controlled pawl 48 is carried by the operating handle 47, said pawl being arranged to coöperate with the ratchet wheel 45 to effect rotation 45 of the shaft 36 in either direction. The handle or lever 47 may be held in vertical position, when not in use, by a short section of chain 48 carried by a cross bar 49 secured to the said uprights 41. Outside of the 50 operating lever 47, the shaft 36 has an extended squared section 50 by which the shaft may be operated with a claw bar or other tool, if same should become necessary at any time by reason of failure of the operating 55 ratchet mechanism.

In actual practice, the ratio of the pinion 35 to the gear 34 will preferably be made 1 to 2 so as to increase the leverage ratio and render it easier for the operator to effect closing and opening of the doors.

With my construction, it will be observed that the operator may stand upon the end sill and effect the closing and opening of the doors without danger of injury either 60 from the operating mechanism itself or from

adjacent cars. The arrangement is also unusually compact and all of the parts are so located as to be free from injury from the discharged loads and furthermore the operating mechanism does not utilize any of the 70 load-carrying space of the car but on the contrary is placed in space that is ordinarily not utilized. As will be understood by those skilled in the art, the pawl 48, as shown in Fig. 1, is positioned so as to effect opening of the doors when the operating handle 47 is swung to the left as viewed in Fig. 1. This produces a counter-clockwise rotation of the pinion 35 and a clockwise rotation of the gear 34. After the shafts 22 have been 80 partially rotated and sufficiently to release the self-locking linkages, the doors will fly open under the effect of the load and this is carried out without danger to the operator since the shaft 36 will rotate in a counter-clockwise direction and the ratchet wheel 45 will run freely under the pawl 48.

I have herein shown and described what I now consider the preferred manner of carrying out the invention but the same is 90 merely illustrative and I contemplate all changes and modifications that come within the scope of the claims appended hereto.

I claim:

1. In a dump car having a longitudinally 95 extending central ridge and side dumping hopper doors; the combination with a longitudinally and horizontally extending shaft disposed beneath the apex of said ridge, one end of said shaft terminating between a bolster and end sill at one end of the car; of connections between said shaft and the doors; a second short shaft at said end of the car extending horizontally, said short shaft having its outer end terminating above 100 and adjacent to said end sill and its other end longitudinally overlapping the adjacent end of said first shaft; means at the outer end of said second shaft adapted to lock the latter; pawl and ratchet mechanism, including a lever, for rotating said second shaft, said lever normally extending upwardly from said second shaft and operable by the user when the latter is standing on said end sill; and reduction gearing operatively interposed between said overlapped portions of the shafts.

2. A dump car having a hopper provided with sloping end walls and a longitudinally extending centrally disposed ridge, said car having also side dumping hopper doors; a longitudinally and horizontally extending main shaft disposed beneath the apex of said ridge and located above the tops of the draft sills, one end of said shaft being extended 120 to a point between a bolster and an end sill of the car; connections between said main shaft and the doors; a gear on the end of said main shaft nearest the end sill; a short horizontally extending operating shaft hav- 125

ing a pinion thereon coöperable with said gear; a housing and bearing bracket for said pinion, gear and shafts; and means, accessible for operation when the operator is 5 standing upon the end sill, for effecting rotation of said operating shaft.

3. A dump car having a hopper provided with sloping end walls and a longitudinally extending centrally disposed ridge, said car 10 having also side dumping hopper doors; a longitudinally and horizontally extending main shaft disposed beneath the apex of said ridge and located above the tops of the draft sills, one end of said shaft being ex- 15 tended to a point between a bolster and an end sill of the car; connections between said main shaft and the doors; a gear on the end of said main shaft nearest the end sill; a short horizontally extending operating shaft 20 having a pinion thereon coöperable with said

gear and located above said main shaft; a housing and bearing bracket mounted on the draft sills for said pinion, gear and shafts; means, accessible for operation when the operator is standing upon the end sill, 25 for effecting rotation of said operating shaft, said means including a ratchet wheel on the outer end of said operating shaft, an operating handle oscillatably mounted on said shaft, and a pawl carried by said handle and 30 coöperable with said ratchet wheel, said handle swinging in a vertical plane above the end sill.

In witness that I claim the foregoing I have hereunto subscribed my name this 9th 35 day of August, 1920.

ARGYLE CAMPBELL.

Witness:

P. M. MERRICK.
